UNITED STATES PATENT OFFICE.

JAMES BRITTON, OF GREEN POINT, NEW YORK, ASSIGNOR TO T. W. BURGER,
OF NEW YORK, N. Y.

DESIGN FOR A TEA-CAN.

Specification forming part of Design No. 6,235, dated November 5, 1872.

To all whom it may concern:

Be it known that I, JAMES BRITTON, of Green Point, in the county of Kings and State of New York, have invented a new and original Design for a Tea-Can, of which the following is a specification:

Figure 1 is a front view, and Fig. 2 a horizontal section of a tea-can containing my new design.

Similar letters of reference indicate corresponding parts.

This invention relates to a new form of face

piece or front of a sheet metal or wooden tea-can. It consists in making said face piece or front *a* in form of a double ogee, as shown in Fig. 2, so that the effect indicated in Fig. 1 will be obtained.

I claim as my invention—

The design for the double-ogee tea-can front, as shown.

JAMES BRITTON.
